UNITED STATES PATENT OFFICE.

JOHN E. WILLIAMS, OF DAYTON, OHIO.

WEATHER-STRIP FOR WINDOWS.

No. 919,509.

Specification of Letters Patent.

Patented April 27, 1909.

Application filed April 27, 1908. Serial No. 429,372.

To all whom it may concern:

Be it known that I, JOHN E. WILLIAMS, citizen of the United States, residing at Dayton, in the county of Montgomery and State 5 of Ohio, have invented certain new and useful Improvements in Weather-Strips for Windows; and I do declare the following to be a full, clear, and exact description of the invention, such as will enable others skilled 10 in the art to which it appertains to make and use the same, reference being had to the accompanying drawings, and to the figures of reference marked thereon, which form a part of this specification.

15 This invention relates to new and useful improvements in weather strips for windows.

The object of the invention is to provide a metallic weather strip of such a construction as to effectually prevent air and dust from 20 entering between the window sash and frame or parting strip.

By the use of my improved weather strip, the air is prevented from initially entering between the parting strip and the weather 25 strip, the object being to provide a weather strip that will exclude any initial entrance of the air around the parting strip and between the parting strip and the weather strip.

In the accompanying drawings,—Figure 1, 30 is a horizontal sectional view of one side of the window frame above the lower or movable sash. Fig. 2, is an enlarged horizontal sectional view through a portion of the window frame, lower sash, parting strip and the 35 weather strip. Fig. 3, is an enlarged cross sectional view of the movable weather strip attachable to the window sash. Fig. 4, is a similar view of the stationary weather strip attachable to the window frame and the 40 sash-parting strip and fitting within the sash-weather strip.

In a detail description of the invention, similar reference characters indicate corresponding parts.

45 Two metallic strips are assembled with each window sash, one fitting within the other, and when so assembled they provide an effective barrier to the entrance of any air or dust at the outer side of the parting strip.

50 One of these metallic weather strips, to-wit—that shown in Fig. 3, consists of a channel strip having two sides 1 and 2 with an intervening V-shaped recess, and the outer side being overlapped by a portion 3 which 55 terminates in a right angled extension 4. The side 1 of this strip terminates in a longi-

tudinal right-angled fold 5 which is provided with a counter-sunk opening through which a screw 6 or a suitable number of such screws penetrate in attaching the strip to the window sash 7. The window sash on the outer side and at the longitudinal edges is provided with suitable chamfers or grooves to receive the weather strip so formed, one portion of which, to-wit—the overturned portion 5 being attached to the window sash by a suitable number of counter-sunk screws 6, and the other portion or terminal 4 of said weather strip being secured to the window sash by projecting it into that portion of the 70 groove in the window sash provided therefor. The strip coöperating with the strip thus described, projects within the window sash strip and is bent to form two longitudinal portions 8 and 9 which conform to the 75 window sash strip and the edges or terminals 10 and 11 of which are bent at right angles. The edge or terminal 10 is secured to the window frame on each side of the sash by a suitable number of nails 12, and the edge or 80 terminal 11 is projected into a suitable groove in the parting strip 13, which strips as is well known separate the upper and lower sashes of the window. It will thus be seen that the weather strip shown in Fig. 4, 85 is stationary and projects within the movable weather strip on the window sash. The terminal 11 extending into the parting strip 13 excludes the passage of any air or dust between the parting strip and the window sash 90 and frame. The terminal 4 of the sash window strip, together with the outer overlapped portion 3, prevents air or dust from entering between the outer face of the window sash and the outer side of the parting strip, and 95 the two weather strips combined and attached as shown and described, provide an efficient barrier to the possible entrance of air or dust.

The metallic strips thus described are constructed of a suitable quality of sheet metal, and the application of said strips does not necessitate any material change in the window structure, either the window frame or the sash, beyond providing the necessary 100 grooves in the window sash for the sash strip.

Having described my invention, I claim:

1. In a weather strip, a movable strip attachable to a window sash and comprising a 110 metallic channel strip, one side of which is overlapped throughout its length and ter-

minates in a right-angled extension which is secured to the window sash, and the other side of which terminates in substantially a longitudinal right-angled extension which is secured to the window sash, and a metallic channel strip projected into the sash strip and having one side thereof terminated at a right angle and secured to the parting strip, and the other side thereof terminating in substantially a right angle and secured to the window frame.

2. In a weather strip for windows, a movable strip bent to provide a longitudinal channel, one side of said strip being overlapped throughout its length and lying adjacent to the window sash parting strip, said overlapped portion terminating in a tongue which is secured in the window sash, and the other side of said strip terminating in a tongue which is secured to the edge of the window sash, a stationary weather strip projected into the longitudinal channel of the

movable weather strip and having one longitudinal edge thereof secured to the parting strip and the other longitudinal edge secured to the window frame.

3. In a weather strip for windows, a metallic strip bent longitudinally to provide a V-shaped groove in cross section, the outer side of said strip being overlapped with the terminal of the overlapped portion projected into the side of the sash, and the inner side of said strip being secured to the edge of the sash, a second metallic strip projected into the groove of the sash strip, the outer side of said last-named strip being secured to the parting strip, and the inner side thereof being secured to the window frame.

In testimony whereof I affix my signature, in presence of two witnesses.

JOHN E. WILLIAMS.
